CLAIM

The ornamental design for a blood test kit, as shown and described.

DESCRIPTION

FIG. 1 is a front perspective view of a blood test kit showing the new design.

FIG. 2 is a top plan view thereof.

FIG. 3 is a bottom plan view thereof.

FIG. 4 is a left side view thereof.

FIG. 5 is a right side view thereof.

FIG. 6 is a front end side view thereof; and,

FIG. 7 is a back end side view thereof.

The broken lines seen on the top of the blood test kit are included for the purpose of illustrating portions of the blood test kit that form no part of the claimed design. The broken lines seen on the bottom of the blood test kit are included for the purpose of illustrating a boundary of an unclaimed area of the blood test kit that forms no part of the claimed design.
